Des. 212,420
Patented Oct. 15, 1968

212,420

HOLDER FOR EVAPORATIVE BLOCKS

Norman E. Wilson, University City, Mo., assignor to The Puro Co., Inc., St. Louis, Mo., a corporation of Missouri

Filed Jan. 11, 1968, Ser. No. 10,131

Term of patent 14 years

(Cl. D23—150)

FIG.1

FIG. 2

FIG. 3

FIG. 4

FIG. 1 is a front elevational view of a holder for evaporative blocks;

FIG. 2 is a rear elevational view thereof;

FIG. 3 is a side elevational view thereof;

FIG. 4 is a perspective view thereof showing the retaining flap in its open position;

FIG. 5 is a front elevational view of a modified holder for evaporative blocks;

FIG. 6 is a rear elevational view thereof; and

FIG. 7 is a side elevational view thereof.

I claim:

The ornamental design for a holder for evaporative blocks, as shown and described.
